UNITED STATES PATENT OFFICE

168,217

CABINET FOR AN AMUSEMENT GAME APPARATUS

Lyndon A. Durant, Chicago, Ill., assignor to General Patent Corporation, Chicago, Ill., a corporation of Illinois

Application July 16, 1951, Serial No. 15,897

Term of patent 14 years

(Cl. D34—5)

To all whom it may concern:

Be it known that I, Lyndon A. Durant, a citizen of the United States and a resident of Chicago, in the county of Cook and State of Illinois, have invented a new, original, and ornamental Design for a Cabinet for an Amusement Game Apparatus, of which the following is a specification, reference being had to the accompanying drawings, forming a part thereof, and in which:

Fig. 1 is a perspective view of a cabinet for an amusement game apparatus showing my new design;

Fig. 2 is a top plan view thereof; and

Fig. 3 is a side elevational view thereof. The back (not shown) is substantially plain.

I claim:

The ornamental design for a cabinet for an amusement game apparatus, as shown and described.

LYNDON A. DURANT.
